UNITED STATES PATENT OFFICE

THEODORE BIRKENMAIER, OF ST. LOUIS, LESTER PIERCE BOLL, OF MAPLEWOOD, AND HERBERT H. WEFELER, OF ST. LOUIS, MISSOURI, ASSIGNEES TO W. N. MATTHEWS CORPORATION, OF ST. LOUIS, MISSOURI, A CORPORATION OF MISSOURI

SWITCH

Application filed April 21, 1928. Serial No. 271,770.

This invention relates to switches, and with regard to certain more specific features, to a fuse switch enclosed in an improved box.

Among the several objects of the invention may be noted the provision of an improved type of a fuse switch of maximum simplicity and ruggedness having a configuration including no hinge pins or lugs for the switch per se, nor fastening bosses; the provision of a switch of the class described having simplified door controlling means; and the provision of a fuse switch of the class described in which there is minimum danger of the current path being shortened between contacts. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a vertical section taken through a closed switch box and fuse cartridge comprising the invention;

Fig. 2 is a front elevation of Fig. 1, certain portions being broken away;

Fig. 3 is a bottom plan view of Fig. 1;

Fig. 4 is a view similar to Fig. 1, showing the door open and a fuse cartridge in partially removed position; and,

Fig. 5 is a cross section taken on line 5—5 of Fig. 1.

Similar reference characters indicate corresponding parts throughout the several views of the drawings.

Referring now more particularly to Fig. 1, there is illustrated at numeral 1 a box, composed of non-conducting material, preferably of porcelain. The box in its finished commercial form is preferably of a unitary construction, the various members thereof being baked together and comprising a back 3, a backwardly sloping top 5, side walls 7 and a septum 9. Recesses 11 are provided in the rear for cementing on suitable supporting

means. The outer surfaces of the side walls 7 are provided with elevations 8 for increasing the leakage path. The forward opening in the box has edges in which are formed longitudinal depressions or recesses 13 for receiving the extending edges 14 of a door 15, the door being so formed as to come flush with the front of said box 1. By this means a tortuous crack, rather than a straight one is effected between the door and box, by means of which a better enclosing effect is had. The door 15 is hinged at the top of the box by means of a pin 17. At its lower end it is provided with an external finger piece 19 for opening and closing purposes.

One of the novel features of the invention comprises a pair of resilient detents 21 fastened to the upper end of said door 15. The detents are preferably formed with a cross strip 22 for fastening purposes. Each detent is preferably of curved form and is positioned nearly flush with the inner faces of the side walls 7 of the box, except that it has a bent portion 23, the effect of which portion 23 is to press against the said inner faces so as to spring the detents 21 slightly inward and thereby frictionally hold the door shut.

Also, when the door is drawn open, as illustrated in Fig. 4, then the bent or curved portions 23 of the detents spring outwardly and drop into their respective longitudinal door recesses 13. The door is thus held in open position. The economy of this construction is apparent, because it may be seen that the same recesses 13 that serve as a door stop and to more completely close the box against weather, also serve as recesses for the action of the detents 21.

Cemented into the inside of back 3 of the box 1 are suitable line terminals 25, comprising wire sockets 27 and spring clips 29. The sockets 27 are arranged with cross passages 31, each of which is laterally tapped for set screws for wire holding purposes. The pair of set screws provided for each socket 27 may be used with either passage 31, whereby wires may be brought in from either side of the switch through either combination of openings 33, or from one side only.

The spring clips 29 are of the type adapted

to receive therebetween in electrical contact the flat sided terminal engaging elements 35 of the fuse cartridge C. The cartridge includes the upper element 35 having screw means 37 thereon for holding a fuse wire 38 in electrical contact. This upper element is also formed with a bridge portion 39 for hooking on an insulated tool 40 for removing and applying the cartridge. A long, gas-expulsive insulating tube 41 is fastened to the upper engaging element 35 and surrounds said fuse link 38 down to a hair pin turn 43 on the latter.

The insulating tube 41 passes with a snug fit through the lower terminal engaging element 35. It is not held to the same with any device such as a set screw, because these have been found to damage the tube and promote leakage, so that an arc (such as is formed upon blowing) connects the terminals 35 over the shortest possible distance, namely through the portion of the tube 41 between said terminals.

Next to the long tube 41 is a short insulating tube 45 which is held to the lower terminal 35 by means of a set screw 47. A pin 49 composed of fiber or other insulating material is then placed through a rearward extension 51 of the lower terminal 35 in such a way as to partially intersect the material of both tubes 41, 45. The intersection is not enough to completely perforate the two walls (see Fig. 3).

The function of the intersecting pin 49 is to prevent the long tube 41 from turning or dropping, inasmuch as said tube has only a frictional engagement with the lower terminal 35. Hence the previous weakness of having a set screw engage the tube 41 is eliminated. The fact that the tubes 41 and 45 are engaged by set screws at the terminals themselves makes no material difference because possible current leakage at those points will not shorten the effective arc.

The lower terminal 35 has an upper extension 51 which serves as a fastening for the fuse, fastening being accomplished by means of the screw plug 53.

A further improvement of the lower terminal 35, taken in connection with the septum 9, consists in said lower and rearward extension 51, which in effect comprises two follower lugs 55, one on each side of the tube 41. These lugs engage the upper forwardly sloping surface of the septum 9. This upper surface, composed of porcelain, similar to the remainder of the box, is preferably glazed and is therefore smooth. It is to be understood that the septum may be constructed of other material such as fiber, bakelite or other insulating material.

The septum 9 is provided with an opening 57 having an upper beveled portion 59 forwardly and a lower beveled portion 61 rearwardly, said opening being adapted to re-

ceive the lower ends of the tubes 41, 45 snugly but not tightly. The fit between the lower end of the cartridge and said opening 57, when the latter is canted forwardly (Fig. 4), is rather loose, while when the cartridge is in vertical or terminal engaging position, the fit is snug enough to substantially separate the interior and exterior of the box.

It will be seen that the septum is not at the lowermost region of the box 1 but is raised somewhat, so that when the cartridge is in terminal engaging position, then the lower end of the cartridge, for purposes of protection, is within the confines of the back 3, side walls 7 and door 15.

The switch may be supplied with a fuse cartridge by opening the door to the Fig. 4 position and inserting the lower end of the cartridge through the opening in the septum as illustrated in Fig. 4. The lugs 55 limit the degree of insertion. This is an easy operation because the fit is loose.

When the lugs strike the septum, the operator pushes the cartridge back into the Fig. 1 position with the terminal engaging elements 35 within the confines of the terminals 29. At this time the lugs 55 ride up on the sloping septum with the cartridge pivoting at point X (Fig. 4) so that there is always attained a proper and accurate engagement. No high degree of skill nor care needs be exercised in pushing home the cartridge.

Removal is effected by applying the tool hook at bridge 39 and drawing down the cartridge. It pivots on the lugs 55 until contact is broken and then falls forward to a position slightly beyond the Fig. 4 position. After this the cartridge may be pulled out of the septum opening 57 by hand or with the tool.

The advantage of this construction is that no hinge pins or the like are used for swinging the cartridge. It greatly simplifies the manufacture. Also, the cartridge is positively placed in a position where the lower open ends of the tubes are outside of the box, so that when the cartridge blows gases are not engendered within the box.

It is to be understood that a double tube type of fuse or switch cartridge is not the only one which may be used with the invention herein set forth. Single tube and tubeless cartridges may be used as well as multi-tubed ones of any number of tubes, the primary requisite being a proper fuse mounting.

In view of the above, it will be seen that the several objects of the invention are achieved and other advantageous results attained.

As many changes could be made in carrying out the above constructions without departing from the scope of the invention, it is intended that all matter contained in the above description or shown in the accompany-

ing drawings shall be interpreted as illustrative and not in a limiting sense.

We claim:

1. A switch comprising a box, line terminals therein, a fuse cartridge having terminal engaging elements, a septum in the box having an opening therein adapted to receive therethrough one end of said cartridge and means on the cartridge adapted to engage said septum to be guided thereby to guide the terminal engaging elements into the line terminals.
  2. A switch comprising a box, line terminals therein, a fuse cartridge having terminal engaging elements, a forwardly sloping septum in the box having an opening therein adapted to receive therethrough one end of said cartridge and means on the cartridge adapted to engage said septum to be guided upwardly thereby to guide the terminal engaging elements into the line terminals, whereby said cartridge may be moved angularly to permit insertion and removal.
  3. A switch comprising a box, line terminals therein, an explosive fuse cartridge having terminal engaging elements, a septum in the box having an opening therein adapted to receive therethrough the explosive end of said cartridge to permit angular movement of the cartridge, said septum being located at a distance above the lower edges of the box and having a slope, and means on the cartridge engaging the septum for guiding the movement of said cartridge.
  4. A switch comprising a box, line terminals therein, a fuse cartridge having terminal engaging elements, a septum in the box having an opening therein adapted to receive therethrough one end of the cartridge and means comprising an integral part of one of said terminal engaging elements adapted to engage said septum to be guided thereby, said box, including the septum, being composed of insulating material.
  5. In a switch box, a switch cartridge for use in the box, a septum for the box having an opening therein adapted to receive a part of the cartridge so as to permit angular swinging thereof, the contour of said opening being such as to permit free movement of the cartridge under conditions of application but to substantially separate the inside of the box from the outside thereof in connection with the cartridge when said cartridge is positioned entirely within the box and guiding means on the cartridge for engaging said septum.
  6. In a switch box, a switch cartridge for use in the box, a septum for the box having an opening therein adapted to receive a part of the cartridge so as to permit angular swinging thereof and to function as a fulcrum therefor and means on the cartridge engaging said septum for guiding purposes.
  7. In a switch box, an explosive fuse car-
- tridge having terminal engaging elements, line terminals within the box adapted to be engaged by said terminal engaging elements, a forwardly sloping septum for the box at its lower end, a door for the box hinged at the upper end, said septum having an opening therein adapted to receive therethrough the explosive end of the cartridge, the contour of said opening being such as to permit free movement of the cartridge under conditions of application but to substantially separate the inside of the box from the outside thereof in connection with the cartridge when said cartridge is positioned entirely within the box, said opening functioning as a fulcrum and guiding means on the cartridge for engaging said septum, whereby the engaging elements are guided to cooperate with the line terminals.
8. In a switch box, a box portion having forward edges, recesses in said edges, a door hinged to the front of the box having extending portions engaging said recesses, at least one spring detent on said door engaging the inner wall of the box and adapted to spring into one of said recesses upon opening the door.
9. A switch box of the class described comprising a unitary porcelain box, a door therefor, said box comprising a back, top, side walls and a sloping bottom, said bottom comprising a septum completely defining independently of said door an opening adapted to receive a cartridge or the like.
10. A switch box of the class described comprising a unitary porcelain box, a door therefor, said box comprising a back, top, side walls and a sloping bottom, said bottom comprising a septum completely defining independently of said door an opening adapted to receive a cartridge or the like, and line terminals in the box, said complete definition of the opening by the bottom providing a reaction portion for effecting engagement of a cartridge with said line terminal.
- In testimony whereof, we have signed our names to this specification this 18th day of April, 1928.
